UNITED STATES PATENT OFFICE.

FREDERICK L. MCGAHAN, OF LOS ANGELES, CALIFORNIA.

TURBINE.

1,372,305.

Specification of Letters Patent. Patented Mar. 22, 1921.

Original application filed October 14, 1918, Serial No. 258,127. Divided and this application filed December 8, 1919. Serial No. 343,355.

To all whom it may concern:

Be it known that I, FREDERICK L. MCGAHAN, a citizen of the United States, residing at the city of Los Angeles, in the county of Los Angeles and State of California, have invented certain new and useful Improvements in Turbines, of which the following is a specification.

This is a division of an application filed by me October 14, 1918, serially numbered 258,127, that issued as Patent 1,324,427, on December 9, 1919.

This invention relates to a steam turbine of the radial impulse type, and is illustrated as applied to the auxiliary driving of a locomotive engine, with the construction suitable for such application by means of which more power is derived for the said purpose and applied thereto, not only because of the use of the said turbine as part of the driving mechanism but, also, because of the application of the power through a plurality of turbines (where desired) and a plurality of wheel groups, which results in greater power being exerted upon the train by the locomotive. All this is accomplished with an economy of steam, not only because steam is used more than once for power and afterward can be used for heating the train, but, also, because the herein-described mechanism enables the derivation of power from steam of lower pressure than is now useful for the purpose, whereby, as may be said, all the power of the steam (instead of, as now, only part of its power) is utilized. Moreover, this mechanism eliminates wasteful and objectionable gas, smoke, sparks, and cinders by drawing the same out of the firebox and returning the solid particles thereto for further combustion. Other economies, advantages, and improvements will hereinafter appear.

In the accompanying drawings forming part of this specification and in which like numbers of reference denote like parts wherever they occur,

Figure 1 is a side elevation of a quadruple driven locomotive illustrating the application of the steam turbine;

Fig. 2 is a vertical section of the turbine taken on the line 2—2 in Fig. 3;

Fig. 3 is a section taken on the line 3—3, Fig. 2;

Fig. 4 is an enlarged plan view of the governor; 55

Fig. 5 is an elevation of the governor taken on the line 5—5, Fig. 4;

Fig. 6 is an enlarged fragmental sectional view around the rotor valves taken on the line 6—6, Fig. 7; 60

Fig. 7 is an enlarged fragmental sectional view taken on the line 7—7, Fig. 6;

Fig. 8 is a view taken on the line 8—8, Fig. 6;

Fig. 9 is a similar section like Fig. 2, 65 illustrating a modified form of governor and rotor valves, taken on the line 9—9, Figs. 10, 11, and 12;

Fig. 10 is a plan section, taken on the line 10—10, Fig. 9; 70

Fig. 11 is a plan section, taken on the line 11—11, Fig. 9;

Fig. 12 is a plan section, taken on the line 12—12, Fig. 9;

Fig. 13 is an enlarged fragmental sectional view around the modified form of 75 rotor valves, taken on the line 13—13, Fig. 15;

Fig. 14 is a view taken on the line 14—14, Fig. 15; 80

Fig. 15 is an enlarged fragmental sectional view, taken on the line 15—15, Fig. 13;

Fig. 16 is a diagram, illustrating a development of the circular cam, for tripping 85 the valve levers;

Fig. 17 is a similar diagram;

Fig. 18 is also a similar diagram;

Fig. 19 is an enlarged view of the governor gear segments; 90

Fig. 20 is a fragmental sectional perspective of the fan;

Fig. 21 is a section on the line 21—21, Fig. 1; and

Fig. 22 is a section on the line 22—22, 95 Fig. 1.

The locomotive 1 is provided with the customary driving-wheels 2 and forward truck-wheels 3. Driving-wheels 2 are driven from cylinder 5 in the usual manner. The 100 tender truck-wheels are in two sets, one set being driven by the other. Thus it will be seen that a quadruple-drive is applied to the locomotive, the same steam being used for all, and may be afterward used for heating 105 the train. By the system herein described

a greater proportion of the energy of the steam is utilized for driving purposes than is attained in prior locomotives, so much so that this apparatus derives driving force 5 from the steam until the steam is reduced to only four or five pounds' pressure, after which it may be used for heating, as above stated.

A turbine 6, which rotates the shaft 7, 10 drives the truck-wheels 3; and the turbine 8 which rotates the shaft 9, drives the truck-wheels 4. Both these turbines are of the same construction, with the exception that turbine 8 has no fan or smoke pipe, as hereinafter described. The locomotive 1 is adapted to travel in either direction, which is particularly true in view of the location of one of the said turbines at each end thereof.

20 The smoke stack 10 will normally not be used, because of the draft of smoke and cinders as hereinafter described and the return of the cinders to the fire-box 11 by an automatic screw-stoker (not shown) and the mixture of the smoke with the steam in the turbine 6.

The initial superheated steam is conveyed from the boiler 12 through the manifold or divider 13 to and through the pipes 14 and 15 to both sides of the locomotive and admitted to cylinder 5 and after said steam has been used in cylinder 5 to drive the piston rod 16 and thus the main driving-wheels 2 in the customary manner, the steam exhausts from said cylinder 5 into the passages 17 and 18, leading to pipes 19. Said passages are conveniently connected to the intake pipes 19 of the turbine 6. Therefore the pony truck turbine 6 uses an intermediate pressure of steam, which is the exhaust from cylinder 5. This steam passes through pipe 19 and thence into the chamber 20 surrounding the revoluble rotor 21 having helical grooves in its surface adapted to receive frictional and impelling contact from the incoming steam, thereby deriving its rotary motion and driving shaft 7 which is connected to trucks 3.

50 The turbine 6 can be cut in or out by use of valves 22 and 23, which are operated from the cabs through reach-rods 24 by any convenient method.

Having thus energized the turbine 6, the steam passes through exhaust pipes 25 to 55 energize turbine 8, the said pipes 25 being located on each side of the locomotive 1. The rotary motion of rotor 21 rotates shaft 9, which thereby drives truck-wheels 4, the righthand set of which in Fig. 1 is driven 60 from the lefthand set in the said figures, by any convenient method. Driving of the said wheels may be accomplished in any other suitable manner, as, for instance, by beveled gears, a universal shaft, or the like.

It should be understood that the action of 65 turbine 8 on shaft 9 and trucks 4 is the same as that of turbine 6 on shaft 7 and trucks 3, with the exception that truck-wheels 4 are a double set as compared with truck-wheels 3.

70 Each rotor 21 is of substantially the same construction and mounted and connected in substantially the same manner. Upon the support 26 above the trucks is fastened a ball-race 27, which bears the bottom of the 75 rotor 28.

The fan 29 has a hub 90 fixed to the shaft 7 having a plurality of cups 91 adapted to connect to the flange 34.

75 The cups 91 open in the direction toward 80 which they rotate, tending to force the intake. The shape within each cup diverts the air from its direction when admitted to a direction approximately at an angle of 90 degrees thereto.

85 Fan 29 draws hot air, smoke and cinders through pipes 30 from the top of the fire-box 11, into the hollow chamber 50 of the rotor 21, and thereby the steam that enters chamber 20 through pipes 19 is reheated or 90 superheated, because the hot flames and gases heat the metal of the rotor 21 thereby reheating and drying the exhaust steam from the cylinders 5, after the said steam enters the chamber 20. A ball race 27 co-operates 9 with a groove in the bottom 28 of rotor 21 and a groove in supports 26 and 31, also, a ball race 32, co-operates with groove 33 in the flange 34 of the fan 29, and a groove 35 in the rotor housing 36, thereby allowing the 100 rotor 21 to rotate freely as impelled by the action of the steam admitted through pipes 19, upon the helical grooves 37, and, thereby 105 rotating shaft 7, to which is fixed the said rotor 21. After the steam has passed 110 through the chamber 20 of the helical grooves 37, it then passes into the chamber 38 of the support 26 and thence through pipe 25 to 115 turbine 8.

The steam passes through the pipe 25 110 along each side of the locomotive 1 to a vertical portion of the pipe 25 at 39 and through this portion of the pipe to the continuation of pipe 25 numbered as shown in Fig. 1 at 40.

115 The object of this vertical pipe 30 is to provide means of separation of the steam from the water, *i. e.*, to take the humidity out of the steam which is actuated by gravity, the water dropping to the bottom of the 120 T 41 and flowing to a filtering mechanism 42.

This turbine 8 may be run independent of low pressure steam, as it has two connections; the one connection to the pipe 40 125 which is the low pressure steam pipe and the pipe 43 which is connected directly to the superheating coils 44. Thus when the

engine is standing still and turbine 8 is desired to run for the making of electricity, pumping air, or some other reason, by turning off steam from pipe 40 and cutting in 5 high pressure steam from pipe 43 this object can be accomplished. After the steam has passed through the turbine 8 in its specific operation it enters a radiator or condenser 47 through which it passes and 10 emerges as water. The water then passes through pipe 48 in a filter 42, where it is freed from the last traces of boiler scale, 15 residue, and grit, then flowing through pipe 45 to the water-tank 46 of the tender and thence is pumped back into the boiler as distilled water, by any common pump as shown at 49.

Fuel, preferably pulverized, is normally fed into the fire-box 11, through nozzles 11^b, 20 by any mechanical stoker (not shown in the drawings). The smoke, soot, cinders, and the like are drawn into the turbine 6 through the pipe 30, from the fire-box 11, 25 by the suction caused by the fan 29, and are drawn through the said fan into the chamber 50 of the rotor 21.

After the smoke has been drawn into the chamber 50 by action of fan 29 (which also draws the cinders and sparks from the fire-box, flue, or smoke-pipe 30) steam is admitted into the said chamber 50 through as 30 many valve orifices 51 as will properly condense said smoke, sparks, cinders, and soot by its being rapidly revolved and churned 35 therein, so that, after its exit from turbine 6, same may be discharged through a stoker back into the fire-box 11.

Piston compression blades 72 are helical in form and may be of any desired pitch. 40 Said blades 72 are held against the highly ground surface of the rotor housing 36 at 73 by means of flat zigzag springs 74, said springs 74 being tempered to hold blades 72 in a fixed position against the said 45 surface 73.

The opening of valves 52 is accomplished through a flyball governor, having balls 53 on the end of a bell crank lever 54, pivotally bolted to the flange 55 by means of a 50 bolt 56, and having on the short arm of the bell-crank 54, a cam 57 which by means of a groove 58 and a roll 59 raises the sleeve 60, to which is fixed the cam wheel hub 61 of the cam 62.

55 When the governor balls 53 expand by centrifugal force, tension is caused on the springs 63, and as the bell-crank 54 begins to rotate around the pivot bolt 56, the cam 57 with the groove 58 tends to rotate about this said pivot 56, and, the lever 54 being secured to the flange 55, the sleeve 60 tends to ride upward over the shaft 7 of the turbine 6.

The sleeve 60 has fixed thereto a cam 62

which moves therewith. The cam wheel 65 comprises a hub 61, fixed to the sleeve 60 with arms 64 adapted to connect to the cam 62.

Holes 65, reamed in the rotor 21, receive the bushing 66, in which is pivoted the valve bell-crank lever 67, by means of a pivot pin 68. The bell-crank lever 67 has a jaw end 69 adapted to receive the cam 62, and a valve plate 70 adapted to open and close the orifice 51.

75 The cam 62 may have one or more offsets 71, as shown in Figs. 16, 17, and 18, and these offsets 71 can be timed for rests and trippings of the valve lever 67, as the conditions may warrant.

80 The offset position of a valve is shown in dotted lines of Fig. 6.

The path of the steam is indicated by arrows in Figs. 2 and 9, and, as shown, the steam passes through an open valve, while 85 the other two valves are closed; illustrating that one valve may be opened while the other remains closed.

The steam, in its predetermined path, and the smoke pass through the openings 75 between the ribs 76. Ribs 76 are adapted to the hub 77, and the bottom of the rotor 28, and the smoke and gases pass into the chamber 78 of the support 25, and thence into the pipe 79, after which the mixture of smoke, 95 steam, sparks, and soot is carried by steam pressure and fan action to the stoker, to be reburned in the fire-box 11.

On the rotor housing 36, is secured by bolts 81, the cap plate 80, having a center 100 hub 82, in which the shaft 7 rotates; and, at the bottom or smaller diameter of the rotor housing 26, is a flange 83, which is secured to the support 26 by means of bolts 84.

105 On the end of the shaft 7, there is fixed a worm 85 and a worm wheel 86, but it is evident that bevel gears, spiral gears, spur gears, and the like, could be used as well as those shown, with a shaft 87 fixed to the 110 driven member 86, which shaft may be the axle of the wheels 3.

In Fig. 9, a modified form of governor is illustrated having balls 53, bell-crank lever 54, flange 55, bolt pivots 56, gear segments 57^a, teeth 58^a, gear segments 59^a, sleeve 60, and springs 63.

When the centrifugal force, as applied to the balls, becomes so great as to spread the balls, shown in Fig. 11, in dotted lines, then, 120 gear segment 57^a moves gear segment 59^a turning sleeve 60, over the shaft 7 of turbine 6. Shaft 7 has a helical groove 88, in which the roller or lug 89 of the sleeve 60 plays, riding upward and carrying sleeve 60 125 with it as hereinbefore specified.

The action of the cam 62 and valve levers 67 are precisely the same as hereinbefore de-

scribed, with the exception that valve plate 70^a may be of a rectangular shape, covering the orifice 51 and overlapping the bushing 66, as is clearly shown.

- 5 One object of the turbine 6 and the vacuum fan 29 is to create a draft from and through the fire-box, taking by suction any back pressure from the cylinders 5 and the piston blades 72 of turbine 6, giving the 10 same condition that is caused by the jet condenser in the well-known stationary engine. A further object is to draw all smoke, cinders, and sparks through the vacuum fan 29 and to keep a more even draft, just the 15 necessary draft to create and regulate a perfect blaze, in the fire-box and through the flues of the locomotive.

It will be understood by locomotive drivers and engineers that after the superheated 20 steam has passed through the ordinary high pressure cylinders, the steam will have lost only a comparatively small percentage of its mean effective pressure, so that when the steam enters the grooves on the turbine 25 (instead of exhausting into the open air to create a draft), which grooves are helical for two-thirds of the circumference of the said turbine, said steam exerts sufficient force to insure powerful rotation of the said 30 turbine.

It will be understood that the interior of the shell of the turbines inclosing the rotor 21 is ground or otherwise formed perfectly smooth, so that the piston blades 72 will 35 form a tight fit and wear evenly, while serving perfectly to control the steam. Any such contacting parts of the apparatus will be made of a suitable bronze alloy hardened with vanadium, so as to give a good wearing surface with the steel surface of the said 40 shell.

The tender turbine 8 equipped with a fan 29 may be so run while the locomotive is standing still as to blow powdered fuel into 45 the fire-box, instead of the said powdered fuel being drawn thereinto, as hereinbefore described.

A locomotive constructed and operated as hereinbefore described will excel in efficiency and effect a saving of at least one-half of the fuel and one-half of the water 50 and will do away with smoke in cities and sparks that set fire to fields, fences, and buildings along the right-of-way, which, also, obviates sparks and smoke flowing 55 back over the train and inconveniencing the train crew and passengers and obstructing their view.

The locomotive herein described will give 60 all the power for pulling a train that is ordinarily derived from a double or triple-header, thus economizing, because of there being but one locomotive with only its own weight.

65 There is a distinct advantage in power in

applying driving power to wheels located along an increased trackage. While the ordinary locomotive drives only by its driving wheels, this locomotive does not discard that ordinary form of driving, but adds to 70 it driving the pony trucks at the extreme front of the locomotive and the two sets of tender trucks at the rear end of the combined and connected tender and locomotive. This separate driving increases the pulling 75 power of the engine. A great advantage is acquired, also, by the superheating of the steam in the interior of the turbine rotor 21 (chamber 50) of the locomotive turbine 6, due to the draft thereinto by the adjacent 80 fans 29 of the hot air direct from the fire-box through pipes 30.

These features may all be adapted to any locomotive now in existence and one or more of the turbines may be applied by utilizing 85 an additional set of driving trucks on either end of the locomotive, and thus using only the exhaust steam to drive the same.

Almost three times the power will be derived from a locomotive constructed as herein 90 described from the use of the same amount of steam in an ordinary present-day locomotive. By this construction, the heavy and tedious work of the fireman will be abolished, leaving him free to render other 95 assistance to the engineer, such as watching the track and preventing accidents from misplaced switches or obstructions or stock upon the roadway.

The turbine 8 may or may not have a 100 fan 29.

While the turbines are herein illustrated and described as utilized in connection with a locomotive engine, they can be used in other situations, in which event water or 105 steam may be used as the motive power.

Having thus described this invention, it is obvious that many minor changes in the form, arrangement and order of parts and their materials and mode of construction may 110 be made without departing from the spirit of this invention or the scope of the following claims.

I claim:

1. In a turbine, the combination of a stationary hollow member having steam pipes leading thereinto, a rotary conical member having helical grooves, grooved partitions between each of the said grooves, spring 115 pressed abutments in the grooves in each of the said partitions, and a shaft driven by the rotation of the said inner rotatable member.

2. A turbine having in its surface a plurality of helical grooves, grooved partitions between the said grooves, helical abutments 120 within the said last mentioned grooves, a container, and springs adapted to keep the said abutments in contact with the walls of the said container.

3. In a turbine, the combination of a 130

conical container, a conical rotary member therein having helical grooves, helical partitions on the said rotary member and between the said grooves, the said partitions containing each a helical groove, a helical abutment within the said helical groove, and a spring adapted to hold each of the said abutments in contact with the wall of the said container.

4. A turbine comprising an outer shell, an inner rotor, the said rotor having openings therethrough, valves controlling the said openings, a shaft with which the said rotor is adapted to rotate, a member adapted to slide upon said shaft, levers in pivotal connection with the said member and also with the said valves and adapted to move in opposite directions according to the direction of movement of the said member, and a governor connected to the said member and adapted to move it in alternate directions, the said governor being fixed to the said shaft.

5. A turbine comprising an outer shell, an inner rotor, the said rotor having openings therethrough, valves controlling the said openings, a shaft with which the said rotor is adapted to rotate, a member adapted to slide upon said shaft, levers in pivotal connection with the said member and also with the said valves and adapted to move in opposite directions according to the direction of movement of the said member, and a governor connected to the said member and adapted to move it in alternate directions, the said governor being fixed to the said shaft, and cam tripping devices for actuating the said valves.

6. A turbine comprising an outer shell, an inner rotor, the said rotor having openings therethrough, valves controlling the said openings, a shaft with which the said rotor is adapted to rotate, a member adapted to slide upon said shaft, levers in pivotal connection with the said member and also with the said valves and adapted to move in opposite directions according to the direction of movement of the said member, and a governor connected to the said member and adapted to move it in alternate directions, the said governor being fixed to the said shaft, and cam tripping devices for actuating the said valves, the said cam devices being located within the said rotor and extending from approximately one side of its wall to the opposite side and there being a grooved sleeve slidable upon the said shaft in the groove of which the said member is held.

7. A turbine comprising an outer shell, an inner rotor, the said rotor having openings therethrough, valves controlling the said openings, a shaft with which the said rotor is adapted to rotate, a member adapted to slide upon said shaft, levers in pivotal connection with the said member and also with the said valves and adapted to move in op-

posite directions according to the direction of movement of the said member, and a governor connected to the said member and adapted to move it in alternate directions, the said governor being fixed to the said shaft, the said valves being pivoted in the openings controlled by them in the wall of the said rotor.

8. A turbine comprising an outer shell, an inner rotor, the said rotor having openings therethrough, valves controlling the said openings, a shaft with which the said rotor is adapted to rotate, a member adapted to slide upon said shaft, levers in pivotal connection with the said member and also with the said valves and adapted to move in opposite directions according to the direction of movement of the said member, and a governor connected to the said member and adapted to move it in alternate directions, the said governor being fixed to the said shaft, the said valves being pivoted in the openings controlled by them in the wall of the said rotor, the said openings containing bushings in which the said valves are pivoted.

9. A turbine comprising an outer shell, an inner rotor, the said rotor having openings therethrough, valves controlling the said openings, a shaft with which the said rotor is adapted to rotate, a member adapted to slide upon said shaft, levers in pivotal connection with the said member and also with the said valves and adapted to move in opposite directions according to the direction of movement of the said member, and a governor connected to the said member and adapted to move it in alternate directions, the said governor being fixed to the said shaft, the said valves being pivoted in the openings controlled by them in the wall of the said rotor, the said openings containing bushings in which the said valves are pivoted, and the said governor comprising a pair of fly-balls, a lever bearing the said balls, a flange to which the said lever is attached, the said flange being the means of attachment of the said governor to the said shaft and the opposite end of the said lever having gear-teeth, there being gear-teeth upon the above-mentioned member adapted to be actuated by the gear-teeth upon the said lever.

10. A turbine comprising an outer shell, a rotor within said shell, an expansion chamber between said rotor and shell, means for admitting fluid into said expansion chamber to act upon said rotor for rotating the latter, said rotor having a passage therethrough, means for admitting heated fluid through said passage in the rotor, and valve controlled ports in said rotor connecting the expansion chamber with the passage in the rotor.

11. A turbine comprising a shell, a rotor

rotatably mounted in the shell, an expansion chamber between the rotor and the shell, and means for admitting fluid under pressure to said chamber for actuating the rotor, said chamber having an exhaust opening, said rotor having a passage therethrough, means for admitting heated fluids through said passage, said rotor having a series of ports therein connecting said expansion chamber and said passage, valves for controlling said ports, and means controlled by the rotation of said rotor for operating said valves.

12. A turbine comprising a shell, a rotor rotatably mounted in the shell, an expansion chamber between the rotor and the shell, means for admitting fluid under pressure to said chamber for actuating the rotor, said chamber having an exhaust opening, said rotor having a passage therethrough, means for admitting heated fluids through said passage, said rotor having a series of ports therein connecting said expansion chamber and said passage, valves for controlling said ports, and means controlled by the operation of the rotor for opening said valves successively according to the increasing speed of the rotor.

13. A turbine comprising a shell, a rotor within the shell and having a passage therethrough, a shaft in said passage and fixed to said rotor to rotate therewith, an ex-

pansion chamber between said rotor and shell, means for admitting fluid under pressure into said chamber whereby said rotor is rotated, said chamber having an exhaust opening, means for forcing heated fluid through said passage in the rotor, means on said shaft for agitating said fluid in said passage, said rotor having a series of ports therein connecting said expansion chamber and said passage, valves for controlling said ports, and means controlled by the rotation of said rotor for operating said valves.

14. A turbine comprising a shell, a hollow rotor rotatably mounted in the shell, an expansion chamber between said rotor and shell, means at one end of the shell for admitting fluid under pressure into the chamber, said chamber having an exhaust opening at the other end of the shell, spirally arranged vanes on the periphery of the rotor to be acted on by said fluid pressure whereby the rotor is actuated, means at one end of the rotor for forcing heated fluid therethrough, said rotor having a series of ports therein extending longitudinally thereof, valves for controlling said ports, and a speed governor actuated by said rotor for successively operating said valves.

In testimony whereof I hereunto affix my signature.

FREDERICK L. McGAHAN.
